DESIGN FOR A CHEST OF DRAWERS OR SIMILAR ARTICLE

David J. Saltman, Los Angeles, Calif.

Application January 9, 1941, Serial No. 97,896

Term of patent 7 years

To all whom it may concern:

Be it known that I, David J. Saltman, a citizen of the United States, residing in Los Angeles, in the county of Los Angeles and State of California, have invented a new, original, and ornamental Design for a Chest of Drawers or Similar Article, of which the following is a specification, reference being had to the accompanying drawing, forming part thereof.

Figure 1 is a perspective view of a chest of drawers or similar article, showing my new design.

I claim:

The ornamental design for a chest of drawers or similar article, substantially as shown.

DAVID J. SALTMAN.
